Des. 177,748
Patented May 22, 1956

177,748

BUILDING FOR USE IN THE DISPENSING OF FOOD

Andrew J. Ochman, Girard, Ohio

Application December 30, 1954, Serial No. 33,762

Term of patent 14 years

(Cl. D13—1)

Fig. 1

Fig. 2

Figure 1 is a front perspective view of a building for use in the dispensing of food showing my new design; and

Figure 2 is a front elevational view thereof.
The rear of the building is conventional.

I claim:

The ornamental design for a building for use in the dispensing of food, substantially as shown and described.
